TWO-SPEED REVERSIBLE CONTROLLER

Herbert J. Framhein, Chicago, Ill., assignor to
The Yale & Towne Manufacturing Company,
Stamford, Conn., a corporation of Connecticut

Application January 3, 1951, Serial No. 204,165

14 Claims. (Cl. 200—5)

1

This invention relates to controllers for electric industrial trucks, and more particularly to a controller of the class having manually operated elements such as push-buttons through which a number of different conditions may be set up in a motor control circuit as desired by the operator.

It has been customary to provide controllers of the class with two push-buttons, each controlling the operation of a traction motor in one direction, speed changes being obtainable by depressing the proper button in varying degrees.

As one feature of my invention, the controller is provided with two switches, termed primary switches, that are selectively operable by a predetermined movement of two push-buttons, and a third switch termed a common secondary switch that is operated by a further movement of either of the push-buttons. This arrangement is suitable for controlling a second speed circuit operated sequentially after operation of either of two directional circuits which may be of the type disclosed in Patent No. 2,399,605 issued to Charles S. Schroeder on April 30, 1946.

As a further feature, the controller mechanism is inherently self-indexing, whereby the operator may readily sense the condition and operation of the switches with a minimum of attention on his part. This is accomplished by a construction through which a substantial resistance to movement of the push-buttons occurs after operation of the primary switches and prior to operation of the secondary switch. This is an important feature in facilitating smooth and easy operation of motorized trucks.

Another feature of the invention resides in the use of small unitary precision switches of the type having a depressible operating button, these switches being readily replaceable and interchangeable from a mechanical standpoint, so that switches having different contact arrangements or electrical characteristics may be embodied in the controller. Thus, for example, a switch having normally open contacts may be easily substituted for one in which the contacts are normally closed in order to adapt the controller to a circuit having such a requirement.

As still another feature, the switches are so arranged in the controller that the buttons will be positively protected against excessive operating pressure or movement. The two primary switches are mounted at opposite sides of a controller casing in such positions that the depressible switch buttons are movable in a direction at right angles to the movement of the plungers upon which the push-buttons of the controller

2

are mounted. The plungers are formed with recesses into which operating elements for the switch buttons project, so that when the plungers are moved longitudinally these elements will be displaced and held by the outer surfaces of the plungers for operating and holding the switches in operated condition. Inasmuch as the switch operating elements can be displaced no farther than the outer surfaces of the plungers, the movements which can be imparted to the switch buttons will be limited in extent and no damage to the switches can result from excessive forces which may be applied to the push-buttons of the controller. As a part of this feature of the invention, provision is made of means which will serve as a positive stop for inward movement of the plungers before the button of the secondary switch can be depressed so far as to damage the switch.

I have thus outlined rather broadly the more important features of my invention in order that the detailed description thereof that follows may be better understood, and in order that my contribution to the art may be better appreciated.

There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings,

Fig. 1 is an end view showing a preferred form of my improved controller.

Fig. 2 is a side view of the same.

Fig. 3 is a longitudinal sectional view taken on line 3—3 of Figure 1 of the same on an enlarged scale, showing the parts as they would appear when both of the push-buttons are in their outermost or "off" positions.

Fig. 4 is a view similar to Fig. 3, but showing one of the push-buttons depressed to an intermediate position for operating the corresponding primary switch.

Fig. 5 is a view similar to Fig. 4, but showing the depressed push-button in its innermost position for operating the secondary switch while holding the primary switch in operated position.

In the drawing, the numeral 10 indicates a controller casing or body, which is preferably in the

form of a rectangular block of metal or other suitable material shaped to receive other parts of the controller, as will be described.

The primary circuit making and breaking function of the controller is served by a pair of precision type snap switches 11, 12, that have outer terminals 13, and in which the contacts are adapted to be operated by short movements of depressible buttons 14 and 15. These switches 11 and 12 are mounted upon opposite edges of the casing 10 by screws 16 in such a way that the buttons 14, 15, are accessible to operating mechanism in the casing 10 through short transverse bores 17, 18, in the casing.

In order to provide independent manual operation of the switches 11, 12, the casing 10 contains a pair of plungers 19, 20 slidable in parallel longitudinal bores 21, 22, the upper ends of these plungers extending above the casing 10 and having push-buttons 23, 24 secured thereon.

Middle sections of the plungers 19, 20 are reduced to provide annular recesses 25, 26, into which balls 27, 28 in the transverse bores 17, 18, are adapted to project when said recesses are located opposite said bores. The upper ends of the annular recesses, 25, 26, are formed as inclined cam surfaces 29, 30, so that when either of the plungers 19, 20 is depressed, the corresponding ball 27 or 28 will be displaced from the recess 25 or 26 and will operate the corresponding switch button 14 or 15. It will be noted at this point that the plungers 19, 20, cannot displace the balls 27, 28, farther than the outer peripheries of the plungers, so that no excessive movement or destructive pressures can be applied to the switch buttons, 14, 15. This arrangement also permits the operator to sense the operation of the primary switches because of the force required to cam the balls 27, 28, out of the paths of the plungers. Once the recesses 25, 26 have passed the balls 27, 28, the latter will offer negligible resistance to further movement of the plungers. Any adjustment which may be found desirable in the operating points of the switches 11, 12, may be accomplished by varying the thickness of suitable shims 31 applied between said switches and the edges of the casing 10.

It will be understood that the plungers 19, 20 will be normally urged to inactive outer or "off" positions in which the plunger recesses 25, 26 will be opposite the balls 27, 28, so that no pressure will be exerted at that time upon the switch buttons 14, 15. In order to hold the plungers 19, 20 in these outer positions, provision is made of coil springs 32, 33, located in counterbores at the upper ends of the bores 21, 22. The coil springs 32, 33 are seated upon washers at the lower ends of the counterbores and press at their upper ends against cross-pins 34, 35 in the plungers 19, 20. The cross-pins 34, 35, also serve to limit outward movement of the plungers by reason of their abutment with an apertured cover plate 36 secured to the upper end of the casing 10. The cover plate 36 preferably projects laterally of the casing 10, thus providing a flange which may serve for mounting the controller upon a suitable support.

The sequential switching function of the controller is served by a secondary switch 37 of the same precision type as the switches 11 and 12, and having a depressible switch button 38 and outer terminal screws 39. The secondary switch 37 is mounted against the lower end of the controller casing 10 by screws 40 in such a position that the switch button 38 is located in a short bore 41 in

longitudinally extending equidistant relationship between the bores 21, 22.

Operation of the secondary switch 37 is obtained through a pair of slideable inclined pins 42, 43, which project upwardly into the paths of the plungers 19, 20 in such a way that either plunger will engage the upper end of one of the pins when the plunger has been pressed downwardly past the point at which the corresponding primary switch is operated, this position of the plunger 19 being illustrated in Fig. 4. Specifically, the plungers 19 and 20 are formed with additional recesses below the annular recesses 25, 26, to receive the projecting upper ends of the pins 42, 43, the upper end surfaces of these lower recesses forming cams 44 on the plungers for operating the pins. The lower ends of the pins 42, 43, extend into the upper end of the bore 41, and engage the rounded upper portion of a secondary plunger element 45 which is slideable downwardly in the bore 41 for operating the secondary switch button 38. Inasmuch as the pins 42, 43, are movable independently of each other, it will be seen that movement of either of the plungers 19 and 20 downwardly beyond the point at which the switch 11 or 12 is operated will result in operation of the secondary switch 37 sequentially with the operated primary switch.

It should be noted at this point, however, that the inclined positions of the pins 42, 43, will result in an increase in the force which must be exerted upon the plungers in order to operate the secondary switch 37. The force necessary to operate the secondary switch will also be increased to some extent by the friction resulting from a slight lateral movement of the pins 42, 43, upon the cam surfaces 44, and also upon the upper end of the secondary plunger 45. In other words, when the operator has pressed either of the push-buttons 23, 24, inwardly just past the point at which the corresponding primary switch is operated, an increased resistance will be encountered which will inform the operator that the secondary switch 37 will be operated upon further movement of the same push-button. This increased resistance is of greater magnitude than that attending the camming of the balls 27, 28, and will tend to prevent accidental operation of the secondary switch 37, such as would occur if the depressed plunger were moved inwardly further than intended by the operator. This particular construction will not, however, require the operator to apply a strong force merely to hold the switch 37 in operated position. The point at which the secondary switch 37 is operated may be adjusted by varying the thickness of a shim 46 which is interposed between the switch 37 and the lower end of the casing 10, this adjustment serving, of course, to vary the position of the switch button 38 in the bore 41.

It will be noted by reference to Fig. 5 that the plungers 19, 20, will engage the shim 46 immediately after they have operated the secondary switch 37 or, in other words, at the end of their downward movement. Thus, it will be seen that the plungers can impart no excessive movement to the secondary plunger 45 and no damage to the switch can occur because of excessive pressures upon the switch button.

When the controller is used in conjunction with the circuit disclosed in the Schroeder patent hereinbefore referred to, all of the switches, 11, 12, and 37 will be of the type in which the contacts are closed when the switch buttons are pressed inwardly and opened when the buttons

are released. It will be understood, however, that the contacts within the switches may have any suitable arrangement in order to fulfill their desired purpose, and the controller is adapted to provide selective control of substantially any two circuits, with or without sequential or common operation of a third circuit. The controller is also well adapted to provide preliminary operation of any single circuit with respect to a second circuit, as for example by sequential operation of the switches 11 and 37.

Without regard to the specific use to which the improved controller is put, the operator will be afforded a means for readily sensing the condition of the switches at all times, and it is believed that the operation of the controller will be clearly apparent from the foregoing description.

I now claim:

1. In a controller of the class described, a pair of switches, a pair of operating members, means whereby movement of each of said operating members operates one of said pair of switches independently of the other, means for resisting said movement of said operating members, a common secondary switch, means whereby the continued movement of each of said operating members after operation of one of said pair of switches operates said common secondary switch sequentially, and additional means for resisting movement of said operating members during said continued movement whereby the operator may sense the condition of the controller through said operating members.

2. In a controller of the class described, a pair of switches, a pair of operating members movable in predetermined paths, means projecting into each of said paths and displaced from said paths by movement of each of said operating members for operating one of said pair of switches independently of the other, a common secondary switch, and means projecting into said predetermined paths of said operating members and engaged directly by one of said operating members upon continued movement thereof after operation of one of said pair of switches whereby to operate said common secondary switch sequentially.

3. In a controller of the class described, a pair of switches, a pair of manually operable plungers, means projecting into the paths of said plungers and displaced from said paths by movement of each of said plungers for operating one of said pair of switches independently of the other, means for resisting said movement of said plungers, a common secondary switch, means projecting into the paths of both of said plungers and engaged by one of said plungers upon continued movement thereof after operation of one of said pair of switches whereby to operate said common secondary switch sequentially, and additional means resisting movement of said secondary switch by said plungers during said continued movement whereby the operator may sense the condition of the controller through said plungers.

4. In a controller of the class described, a switch, an operating member movable in a predetermined path, an element displaced from said path by movement of said member for operating said switch, means for resisting said movement of said member, a secondary switch, means projecting directly into said predetermined path whereby said secondary switch is operated by further movement of said member sequentially after said first-mentioned switch, additional means resisting movement of said secondary

switch by said operating member during said further movement whereby the operator may sense the condition of the controller through said operating member, and means for stopping movement of said operating member after said secondary switch is operated.

5. In a controller of the class described, a switch, a plunger, means whereby movement of said plunger operates said switch, means for resisting said movement of said plunger, a secondary switch, and means for operating said secondary switch sequentially after operation of said first switch including a pin projecting at an angle into the path of said plunger and engaged by said plunger upon continued movement thereof after operation of said first switch, the angular relationship of said pin to said path contributing added resistance to said continued movement of said plunger in operating said secondary switch.

6. In a controller of the class described, a pair of switches, a pair of plungers, recesses in the sides of said plungers, means projecting into said recesses and displaced therefrom by movement of each of said plungers for operating one of said pair of switches independently of the other, a common secondary switch, and means projecting directly into the paths of said plungers and engaged by said plungers upon continued movement thereof after said first switch operating means has been displaced from one of said recesses whereby to operate said common secondary switch.

7. In a controller of the class described, a pair of switches, a pair of parallel plungers, means whereby movement of each of said plungers operates one of said pair of switches independently of the other, a common secondary switch, a secondary plunger element symmetrically located with respect to said plungers for operating said secondary switch, and a pair of members projecting into the paths of said parallel plungers and engaged by one of said parallel plungers upon continued movement thereof after operation of one of said pair of switches for operating said plunger element whereby to operate said secondary switch.

8. In a controller of the class described, a pair of switches a pair of plungers, cam surfaces on said plungers, means projecting against said cam surfaces and displaced by movement of said plungers for operating one of said pair of switches independently of the other, a common secondary switch, a secondary plunger element for operating said secondary switch, and a member projecting into the path of each of said plungers and engaged by one of said plungers upon continued movement thereof after operation of one of said pair of switches for operating said plunger element whereby to operate said common secondary switch.

9. In a controller of the class described, a pair of switches, a pair of plungers, cam surfaces on said plungers, balls displaced by said cam surfaces through a first movement of said plungers for actuating one of said switches independently of the other, a common secondary switch, and means directly in the path of both of said plungers and engaged upon further movement of the moved plunger after actuation of the actuated switch for actuating said common secondary switch.

10. In a controller of the class described, a pair of switches, a pair of operating members, cam surfaces on said operating members, balls displaced by said cam surfaces through a first move-

ment of said operating members for actuating one of said switches independently of the other, a common secondary switch, a secondary plunger element for operating said secondary switch, and a pair of pins projecting into the paths of said operating members and engaged upon further movement of the moved operating member for operating said secondary plunger element whereby to actuate said common secondary switch.

11. In a controller of the class described, a pair of switches, a pair of plungers, recesses in the sides of said plungers, balls displaced from said recesses through a first movement of said plungers for actuating one of said switches independently of the other, a common secondary switch, and means directly in the path of both of said plungers and engaged upon further movement of the moved plungers after actuation of the actuated switch for actuating said common secondary switch.

12. In a controller of the class described, a pair of switches, a pair of parallel plungers, recesses in the sides of said plungers, balls displaced from said recesses through a first movement of said plungers for actuating one of said switches independently of the other, a common secondary switch, a secondary plunger element intermediate said plungers for operating said secondary switch, and a part of each of said parallel plungers operating said secondary plunger element upon further movement of the moved plunger whereby to actuate said common secondary switch.

13. In a controller of the class described, a casing, a pair of switches mounted on opposite sides of said casing and each having a depressible operating element, a pair of plungers mounted in bores in said casing, recesses in said plungers opposite said depressible elements, balls projecting into said recesses and displaced therefrom by movement of each of said plungers for de-

10

pressing one of said depressible elements independently of the other, a common secondary switch mounted on said casing and having a depressible operating element, and a secondary plunger symmetrically located with respect to the paths of said pair of plungers and actuated by either one of said pair of plungers whereby to operate said secondary switch sequentially after operation of one of said pair of switches.

14. In a controller of the class described, a casing, a pair of switches mounted on opposite sides of said casing and each having a depressible operating element, a pair of plungers mounted in parallel bores in said casing between said switches, recesses in said plungers opposite said depressible elements, balls projecting into said recesses and displaced therefrom by movement of each of said plungers for depressing one of said depressible elements independently of the other, the peripheries of said plungers denoting the limit of the operating movement that can be imparted thereby to the depressible elements of said switches, a common secondary switch mounted on said casing and having a depressible operating element, and a secondary plunger symmetrically located with respect to the paths of said pair of plungers and actuated by either one of said pair of plungers to operate said secondary switch sequentially after operation of one of said pair of switches.
